GOLFER'S ACCESSORY TOOL

John J. West, 296 Monarch Road, Dayton, Ohio

Filed Mar. 7, 1962, Ser. No. 69,125

Term of patent 14 years

(Cl. D34—5)

I claim:

The ornamental design for golfer's accessory tool substantially as shown.
